Primary Examiner — Cynthia Underwood(74) *Attorney, Agent, or Firm* — Margaret Polson Oppedahl Patent Law Firm LLC(57) **CLAIM**

The ornamental design for a double carabiner, as shown and described.

DESCRIPTION

FIG. 1 is a front side elevation view of my new design for a double sided carabiner, with the portions shown in broken lines included for illustrative purposes only and forming no part of the claimed design.

FIG. 2 is a back side elevation view of FIG. 1.

FIG. 3 is a right side elevation view of FIG. 1.

FIG. 4 is a left side elevation view of FIG. 1.

FIG. 5 is a top plan view of FIG. 1.

FIG. 6 is a bottom plan view of FIG. 1.

FIG. 7 is a front perspective view of FIG. 1.

FIG. 8 is a front side elevation view of an alternate embodiment of my new design for a double sided carabiner, with the portions shown in broken lines included for illustrative purposes only and forming no part of the claimed design.

FIG. 9 is a back side elevation view of FIG. 8.

FIG. 10 is a right side elevation view of FIG. 8.

FIG. 11 is a left side elevation view of FIG. 8.

FIG. 12 is a top plan view of FIG. 8.

FIG. 13 is bottom plan view of FIG. 8; and,

FIG. 14 is a front perspective view of FIG. 8.
